COMBINED STORAGE AND DISPLAY RACK FOR AN ELECTRIC KNIFE AND AN ELECTRIC FOOD MIXER

Charles B. Price, Stamford, Conn., and Samuel Braun,
Rye, N.Y., assignors to Scovill Manufacturing Com-
pany, Waterbury, Conn., a corporation of Connecticut

Filed Jan. 30, 1969, Ser. No. 15,564

Term of patent 14 years

Int. Cl. D7—99

U.S. Cl. D44—29

Fig. 1

Fig. 2

*Fig. 4**Fig. 3*

FIG. 1 is a perspective view of a combined storage and display rack for an electric knife and an electric food mixer showing our new design;

FIG. 2 is an enlarged scale right end elevational view;

FIG. 3 is a front elevational view; and

FIG. 4 is a top plan view.

The rear wall of the rack is essentially flat and unornamented.

We claim:

The ornamental design for a combined storage and display rack for an electric knife and an electric food mixer, as shown and described.
